UNITED STATES PATENT OFFICE

154,222

DESIGN FOR A FEET EQUIPPED OUTER GARMENT

Edward E. Tanner, Jr., Chicago, Ill.

Application July 28, 1947, Serial No. 140,562

Term of patent 14 years

(Cl. D3—17)

To all whom it may concern:

Be it known that I, Edward E. Tanner, Jr., a citizen of the United States, residing at Chicago, in the county of Cook and State of Illinois, have invented a new, original, and ornamental Design for a Feet Equipped Outer Garment, of which the following is a specification, reference being had to the accompanying drawing, forming a part thereof:

In the drawings:

I claim:

The ornamental design for a feet equipped outer garment, substantially as shown.

EDWARD E. TANNER, JR.
